UNITED STATES PATENT OFFICE.

WALTER H. THOMAS, OF SPENCER, IOWA.

FOOT ACCELERATOR.

Application filed January 25, 1926. Serial No. 83,602.

The object of my invention is to provide a foot accelerator of simple, durable and inexpensive construction, peculiarly adapted for operating the fuel throttle valve from the footboard of a car.

My device has such structure and arrangement of parts as to adapt it especially for use with Ford cars having the carburetor in which the throttle valve is located at the upper part of the engine.

With this and other objects in view, my invention consists in the construction, arrangement and combination of the various parts of my foot accelerator, whereby the objects contemplated are attained, as herein-after more fully set forth, pointed out in my claims, and illustrated in the accompanying drawings, in which:

Figure 1 shows a vertical, sectional view 20 through the body of a car having an engine shown in side elevation with my improved foot accelerator installed thereon.

Figure 2 shows a top or plan view of the engine and foot accelerator and other parts, 25 the dash and steering post being shown in section.

Figure 3 is a vertical, sectional view taken on the line 3—3 of Figure 2.

Figure 4 is a detail, sectional view taken 30 on the line 4—4 of Figure 3.

Figure 5 is a horizontal, sectional view taken on the line 5—5 of Figure 1; and

Figure 6 is a vertical, sectional view taken 35 on the line 6—6 of Figure 3.

In the drawings herewith, which illustrate one form of my invention and the manner in which it may be installed upon the car, I have used the reference numeral 10 to indicate generally the frame of a Ford 40 automobile.

Supported on the frame is the body having the inclined footboard 11, the dash 12, cowl 13 and instrument board 14. Supported on the frame also is the engine indicated generally by the reference character 15.

At the front of the engine is the radiator 16.

The engine is covered by the ordinary hood 17. On the engine is the carburetor 18, the heating device 18^a, having the cover plate 19, held in place by fastening devices or bolts 19^a, and the intake passage 20 leading to the intake manifold 21.

In the passage 20 is the ordinary throttle valve 22, having the projecting stem 23.

Mounted on the stem 23 is an arm 24, having at one end a projection 25 adapted to engage the intake manifold 21, which thus serves as a stop when the throttle valve is 60 open.

Mounted in the arm 24 on the opposite side of the stem 23 from the extension 25 is an adjusting screw 26, which may be adjusted to engage the intake manifold 21 for 65 limiting the closing movement of the throttle valve.

On the Ford car is the hand throttle control rod 27 mounted in the steering post 28. Fixed on the hand throttle rod 27 is the arm 70 29, which in the ordinary Ford car, is connected with the arm 24 by a link. That link is removed when my device is used.

I will now describe the parts of my improved foot accelerator and the manner of 75 assembling them on the car.

I may use a foot throttle control rod similar to that shown in my co-pending application, Serial No. 80,492, filed January 11, 1926, slidably mounted in the footboard 11, 80 or may use the foot pedal 30 on the substantially U-shaped lever 31, which is projected through an opening 32 in the floor board 11, and is pivoted just below the floor board to the bracket 33, leaving one of its arms projecting downwardly and slightly rearwardly as at 31^a.

Pivoted to the lower end of the arm 31^a is a link or rod 34, which projects forward- 90 ly and downwardly in the car.

One of the bolts by which the heating device cover plate 19 is secured in place is removed, and a relatively long bolt 35 is substituted therefor. (See Figures 1 and 3.)

Centrally pivoted on the bolt 35 is a bell 95 crank lever 36, one arm of which has a pivotal connection with the foot control rod 34. The rod 34 has at its rear end a laterally bent portion 38 extending through a hole in the arm 31^a of the lever 31, and at its forward end a laterally bent portion 39 extended through a hole in one arm of the bell crank lever 36.

An angle bracket 40 (see Figures 1, 5 and 6) is supported on the flange 41 of the carburetor fuel passage 20 by means of the bolt 42^a, by which that flange is secured to the intake manifold.

A pivot pin or the like 42 is mounted in one arm of the flange of the bracket 40 110 and the bell crank lever 44 is pivoted thereon.

Mounted in one arm of the bell crank position (Figure 3) to its dotted line position in that figure against the tension of the spring 62. When the hand throttle lever is operated in the opposite direction, the journal block 70 tends to slide on the rod 60, but the spring 62 actuates the parts of my device for closing the throttle valve.

When the hand throttle lever is operated in the opposite direction, the journal block 70 tends to slide on the rod 60, but the spring 62 actuates the parts of my device for closing the throttle valve.

It will thus be seen that the foot accelerator mechanism may be operated for actuating the throttle control lever 24, and while this actuates the rod 60, it does not affect the arm 29 and the handle to the throttle rod 27.

10   A ball 47 is mounted in the socket 46 and projecting from the ball is

5   the rod 48, having the right-angled extension 49, which has at its end the socket 50 internally screw-threaded. Screwed into the socket 50 is a short link or rod 51 on

10   which is a lock nut 52.

The other arm of the bell crank lever 36 has mounted therein a short rod 53 having at one end the socket 54 of a ball and socket joint. Received in the socket 54 is the ball

15   55 on which is the short rod 56 with the right-angled extension 57 terminating in the internally screw-threaded socket 58 into which is screwed the other end of the rod 51.

15   A short link 59 is pivoted to the arm of the bell crank lever 44.

Pivoted to the upper end of the lever 44 is one end of a transverse rod 60. The rod 60 has a short right-angled extension 61 extended through a hole in the arm 24 and

25   also through a hole in the link 59.

On the bolt 35 is mounted a coil spring 62, one end of which engages one arm of the bell crank lever 36 and the other end of which is arranged under a shoulder 63 of the carburetor structure in such manner as to hold the spring under tension and to normally, yieldingly hold the parts in such position as to hold the throttle valve closed.

35   Rotatably mounted in the arm 29 on the foot throttle control rod 27 as perhaps best shown in Figure 4 is a spindle 64 of a journal block 65, through which the rod 60 is slidably extended, as shown in Figures 3 and 4.

40   The end of the rod 60, which is extended through the journal block 65 is provided with some suitable stop device, as for instance the cotter pin 66 extended through it, and spaced from such stop device a suitable distance is a collar 67 adjustably mounted on the rod 60 and held in any adjusted position by means of a set screw 68.

The parts are so constructed and arranged and assembled on the car that when

50   they are in normal position, the spring 62 yieldably holds the lever 24 in position, when the throttle valve is in its closed position.

The rod 60 is then at its left-hand limit of movement as illustrated in Figure 3.

The collar 67 then stands adjacent to the journal block 65.

When the hand throttle lever is actuated for rotating the rod 27 for the throttle opening operation, the journal block 65 engages the collar 67 and moves the rod 60 from its full line position shown in Figure 3 toward the right to its dotted line position shown in that figure.

55   This swings the lever 24 from its full line

position in that figure against the tension of the spring 62.

When the hand throttle lever is operated in the opposite direction, the journal block 70 tends to slide on the rod 60, but the spring 62 actuates the parts of my device for closing the throttle valve.

It will thus be seen that the foot accelerator mechanism may be operated for actuating the throttle control lever 24, and while this actuates the rod 60, it does not affect the arm 29 and the handle to the throttle rod 27.

When the hand throttle rod is actuated, the throttle lever 24 may likewise be operated, and the foot accelerator parts move freely, except as such movement is resisted by the spring 62 during throttle opening movement.

If the throttle is opened by hand, and the hand throttle rod 29 is then rotated back to its original starting position, the spring 62 will actuate the parts for closing the throttle valve and sliding the rod 60 to the left until the collar 67 stands adjacent to the journal block 65.

Changes may be made in the details of the construction and arrangement of my improved foot accelerator structure without departing from the real invention involved therein, and it is my intention to cover by my claims any modified forms of structure or use of mechanical equivalents, which may be reasonably included within the scope of such claims.

I claim as my invention:

1. The combination of a motor car structure including an engine having a throttle valve near its upper portion, a hand throttle control rod, an arm on said hand throttle control rod, a lever for actuating said throttle, and a foot board, with a foot accelerator structure having a rod adapted to be actuated for longitudinal movement by the foot of a driver, a bell crank lever pivoted on the engine and pivoted to said foot actuable rod, a second bell crank lever, means for operatively connecting said bell crank levers, a transverse rod having a limited sliding action with the arm on said hand throttle rod, and a pivotal connection with said throttle lever, a link pivoted to the second bell crank lever and having a pivotal connection with the throttle lever.

2. The combination of a motor car structure including an engine having a throttle valve near its upper portion, a hand throttle control rod, an arm on said hand throttle control rod, a lever for actuating said throttle, and a foot board with a foot accelerator structure having a rod adapted to be actuated for longitudinal movement by the foot of a driver, a bell crank lever pivoted on the engine and pivoted to said

foot actuatable rod, a second bell crank lever, means for operatively connecting said bell crank levers, a transverse rod having a limited sliding action with the arm on said handle throttle rod and a pivotal connection with said throttle lever, a link pivoted to the second bell crank lever and having a pivotal connection with the throttle lever, one of said bell crank levers being yieldably constrained to move toward one limit of its movement.

3. The combination of a motor car structure including an engine having a throttle valve near its upper portion, a hand throttle control rod, an arm on said hand throttle control rod, a lever for actuating said throttle, and a foot board with a foot accelerator structure having a rod adapted to be actuated for longitudinal movement by the foot of a driver, a bell crank lever pivoted on the engine and pivoted to said foot actuatable rod, a second bell crank lever, means for operatively connecting said bell crank levers, a transverse rod having a limited sliding action with the arm on said hand throttle rod and a pivotal connection with said throttle lever, a link pivoted to the second bell crank lever and having a pivotal connection with the throttle lever, one of said bell crank levers being yieldably constrained to move toward one limit

of its movement, a foot engaging member operatively connected with said foot actuatable rod and adapted to be engaged by the foot of a driver above said foot board. 35

4. The combination of a motor car structure including an engine having a throttle valve near its upper portion, a hand throttle control rod, an arm on said hand throttle control rod, a lever for actuating said throttle, and a foot board, with a foot accelerator structure having a rod adapted to be actuated for longitudinal movement by the foot of a driver, a bell crank lever pivoted on the engine and pivoted to said foot actuatable rod, a second bell crank lever, means for operatively connecting said bell crank levers, a transverse rod having a limited sliding action with the arm on said hand throttle rod, and a pivotal connection 40 with said throttle lever, a link pivoted to the second bell crank lever and having a pivotal connection with the throttled lever, the means for mounting one of said levers on the engine comprising a bolt projecting substantially from the engine, said engine having adjacent thereto a shoulder, a coil spring mounted on said bolt and having its ends engaged respectively with said shoulder and with one end of the bell crank 45 lever on said bolt. 50
